CALCULATING METER FOR ROAD BUILDING

Robert E. Burnham, Hartshorne, Okla., and
George V. Burnham, Whitewright, Tex.

Application February 16, 1939, Serial No. 256,304

1 Claim. (Cl. 33—215)

This invention relates to a calculating meter for road building, and it is an object of the invention to provide a device of this kind to be employed in determining the degree of angle across or transversely of the roadway and which can also be employed with equal facility to calculate the depth of bar ditch and the amount of fall per foot.

Another object of the invention is to provide a device of this kind adapted to be mounted upon a grader and which operates under the action of a pendulum and wherein the meter is so constructed and arranged as to enable the desired calculation to be computed either to the right or left.

The invention consists in the details of construction and in the combination and arrangement of the several parts of our improved calculating meter whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawing, wherein—

Figure 1 is a view in front elevation of a calculating meter constructed in accordance with an embodiment of our invention;

Figure 2 is an enlarged fragmentary sectional view taken substantially on the line 2—2 of Fig. 1;

Figure 3 is a detailed sectional view taken substantially on the line 3—3 of Fig. 2.

As disclosed in the accompanying drawing, C denotes a casing of desired dimensions and which is adapted to be placed upon the frame of a grader substantially parallel with the rear axle at a point rearwardly of the blade cut.

Intersecting the casing and disposed through and held by the front wall 1 and rear wall 2 of the casing are the bolts 3 and 4. These bolts 3 and 4 are spaced apart in a direction lengthwise of the casing C with the bolt 4 at a desired point below the bolt 3.

The bolts 3 and 4 provide a support for the parallel bars 5 disposed on a downward incline as determined by the relative relation of the bolts 3 and 4. The upper portions of these arms 5 freely support a shaft 6 intersecting the space between the arms 5, and fixed to this shaft 6 between said arms 5 is a relatively large pulley 7. Depending from the shaft 6 and fixed thereto is

5 a rock arm 8 of desired length and secured to the lower portion of this arm 8 is a weighted member or poise 9 which will readily swing to the right or left as the transverse tilt of the grader may determine.

10 The bolts 3 and 4 extend beyond the front wall 1 of the casing C and hold in a position overlying the front wall a plate 10. Adhesively or otherwise secured to the outer face of this plate 10 is a dial 11. The bars 5 also freely support a shaft 12 bridging the space between the bars 5 and extending outwardly thru the front wall 1 of the casing C and through the plate 10 and at the axial center of the dial 11. 15 Fixed to the outer or extended end portion of the shaft 12 for rotation therewith are the oppositely directed elongated indices or points 14.

10 The shaft 12 between the members 5 has fixed for rotation therewith a pulley 15 and winding upon this pulley 15, as at 16, is the central portion of a flexible member 17 which is also extended around the pulley 7. The flexible member 17 has its lengths crossed at a point between the pulleys 7 and 15 so that upon rotation of the 20 pulley 7 desired rotation of the pulley 15 is also accomplished.

20 The dial 11 is provided on its outer or exposed face with three concentric circles 18, 19 and 20. This outer face of the dial 11 is also provided with a series of radial lines 21 extending from substantially the center of the dial 11 to the outer annular lines 18 and midway between adjacent lines are the radial lines 22 which extend from the inner circular line 20 to the outer circular line 18.

35 Associated with the outer annular or circular line 18 are the angle degree graduations 23 consecutively numbered to the right and left from the uppermost or top zero point 24. The graduations 23 coacting with the indices or pointers 14 to indicate degree to angle of the roadway in a direction crosswise or transversely thereof and which calculation is obtained, of course, in accordance with the extent of side tilting movement 40 of the grader.

40 The intermediate annular or circular line 15 is provided with the suitably positioned indications 25 whereby may be readily calculated the depth of the bar ditch based on a six feet rear wheel width. These indications, however, can be readily computed in connection with other wheel widths.

45 Associated with the inner circular or annular line 20 are the indications 26 whereby may be readily registered the drop in inches per foot.

Disposed over the plate 10 and applied dial 11 is a cover member M including a rim 27 and a transparent panel or glass 28. The rim 27 is provided with an outstanding lug 29 whereby the rim may be readily attached to the upper bolt 3 while at a diametrically opposed portion the rim 27 is provided with a conventional latch 30 for holding engagement with the keeper 31 carried by the front wall 1 of the casing C. The casing C is adapted to have in the lower portion thereof oil of a consistency to stabilize the pendulating movement of the arm 8 and particularly to prevent excess swinging on rough ground.

From the foregoing description it is thought to be obvious that a calculating meter constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in

carrying out our invention in practice except as hereinafter claimed.

We claim:

5 A calculating meter for road building comprising a casing having front and rear walls, parallel bars within the casing, bolts disposed through the front and rear walls of the casing and through the end portions of the bars for supporting the bars within the casing, said bolts extending beyond the front wall of the casing, a dial plate supported by said extended portions of the bolts, 10 a shaft rotatably supported by the bars and bridging the space therebetween, said shaft extending through the front wall of the casing and through the dial plate, an index carried by said shaft and outwardly of the dial plate, a second shaft rotatably supported by the bars and bridging the space therebetween, pulleys mounted on both of the shafts for rotation therewith, a pendulum 15 carried by the second shaft, and a flexible connection winding upon both of the pulleys but in reverse directions whereby the pulleys are in driven connection.

R. E. BURNHAM.
GEORGE V. BURNHAM.
